[57] ABSTRACT

This invention describes an improved type of anchor for small craft which comprises a plurality of arms with flukes on the end. These are spaced circumferentially around a cylindrical tubular body. The arms are hinged so that they may be moved inwardly until they lie substantially along the body, or pulled outwardly where they are stopped at a preselected angle and

serve as spades or flukes to dig into the sea floor. The body comprises a tubular member which has a longitudinal slot throughout its length and is closed at each end. The support member to which the anchor cable is attached, comprises a rod which has an eye at one end, to which the anchor cable is attached. At the other end is a spherical ball which is of diameter slightly less than the inner diameter of the cylindrical body. The ball is inserted into the tube with the rod fitting into the slot so that the eye extends to the outside. The ends of the cylinder are then closed, as by brazing or welding, so that the ball is locked inside of the tubular body.

The plurality of flukes are arranged unsymmetrically so that on the side of the body corresponding to the position of the slot there are fewer flukes than on the opposite side. When the anchor is lowered by cable the support member will be at the end of the body opposite to which the flukes are attached. As the anchor is lowered it will rest on its bottom tip and the weight of the flukes will cause it to tilt in a direction opposite to that of the slot. With the anchor resting on two of the flukes, if the cable is pulled to the side, they will dig into the sand and mud until the anchor resists further movement. If it should happen that the fluke digs in under a rock or other obstacle, such that it is difficult to pull the anchor out simply by lifting the cable, then the direction of pull on the cable is reversed. This causes the ball to slide to the opposite end of the anchor body and by pulling in that direction the fluke is pulled out of the mud in the opposite direction to which it went in, and can be removed without difficulty.

FOLD UP RETRIEVABLE ANCHOR

BACKGROUND OF THE INVENTION

This invention is in the field of anchors for small craft. More specifically, this invention is concerned with the design of a small anchor which has a plurality of arms or flukes which are hinged to a longitudinal body so that when the anchor is to be stowed away the flukes can be pressed inwardly until they lie along the body and therefore the anchor occupies a very small space. Still more specifically, this invention concerns a design of anchor that can readily be pulled out of the sea floor.

In the prior art there are instances of anchors that are designed with a support means which is slidable along the body of the device so that the anchor can be retrieved by pulling the anchor cable in a direction opposite that in which the anchor was set. Thus, the point of attachment of the anchor cable is moved to the opposite end of the anchor body and therefore provides a pull more or less along the direction of the flukes. However, this design has additional advantages in that the flukes can be hinged since they are in a position circumferentially about the body of the anchor which keeps them out of interference with the motion of the support means along the slot. Furthermore, the point of attachment of the flukes is a short distance away from the second end of the body. Thus the body and the slot extend beyond the base of the flukes and the point of attachment of the pulling cable can then be set beyond the point of attachment of the flukes to provide a positive opposite pull.

SUMMARY OF THE INVENTION

It is a principal object of this invention to provide a simple, small, stowable anchor which has means for positive retrieval even though the anchor flukes are caught in a binding position.

It is a further object of this invention to provide an anchor in which each of the flukes is hinged so that they may lie longitudinally along the body of the anchor.

These and other objects of this invention are realized and the limitations of the prior art are overcome by providing an anchor, the body of which is a long, cylindrical element with a longitudinal slot along one side. The support member comprises a rod of diameter slightly less than the width of the slot. One end of the support member has a sphere attached which has a diameter slightly less than the inner diameter of the cylindrical tube which forms the body. The opposite end of the support member has an eye to which the anchor cable can be attached. The ball of the support member is inserted into the cylinder with the cylindrical rod portion passing through the slot. Both ends of the cylindrical tube are then closed over such as by welding or brazing so that the sphere is locked inside the tubular body and the rod can extend axially out of either end of the body.

A plurality of arms or flukes are hingedly attached near one end, which will be called the base end, the outer end being called the support end. These plurality of arms are hinged in such a manner that they can be placed substantially along the body of the anchor, thereby providing a small circular contour, making the device easily stowable. The shape of the hinged ends of

the flukes is such that in the extended position they are locked against the surface of the cylindrical body, which prevents their extension to any greater diameter. They are hinged by means of a bolt which can be tightened to provide considerable friction to the movement of the flukes so that once extended they will stay extended in the use of the anchor.

BRIEF DESCRIPTION OF THE DRAWINGS

These and other objects of this invention and a better understanding of the principles and details of the invention will be evident from the following description, taken in conjunction with the appended drawings, in which:

FIG. 1 represents an overall view of the anchor of this invention with flukes extended.

FIGS. 2, 3 and 4 indicate three views of the anchor with the flukes compressed and positioned alongside the body of the anchor.

FIG. 5 indicates in schematic form the arrangement of the anchor with four flukes.

FIG. 6 indicates the possible use of a weight on one or more of the flukes which will serve to cause the anchor to fall in the proper direction to apply the flukes to the sea floor.

DESCRIPTION OF THE PREFERRED EMBODIMENT

Referring now to the drawings, and in particular to FIG. 1, there is shown one embodiment of this invention.

FIGS. 2, 3 and 4 show other views of the same embodiment, in each of which there are three arms 6 with spades or flukes 26 which are attached by hinge bolts 7 to pairs of brackets 22, 24, at a position near the base end of a longitudinal body element 10 which comprises a hollow cylindrical tube. The tube 10 has an inner diameter 18 and has a slot 16 which extends for the full length of the body 10. A support member 12, which comprises a rod or stem at one end of which is an eye 9 to which the anchor support cable can be attached. At the other end there is a sphere 14 of diameter less than the inner diameter 18 of the tubular body. The stem 12 of the support member is slightly less in diameter than the width of the slot 16, so that the handle can be pulled completely to the support end 10A of the body, or can be slid along the slot to the base end 10B of the body. The ends of the body are closed off by walls 20, arranged by welding or brazing or such, so that a pull can be made with the stem 12 coaxial with the body and extending out of either end.

The arrangement of the three arms 6 as shown in FIG. 4 is such that the three arms are approximately 90° apart with the slot opposite the middle arm.

In use, the three arms or flukes are pulled outward until the base 28 is pressed tightly against the outer wall of the body. In this way the flukes are wedged so that they resist further pullout, and therefore the flukes are in a strong restraining position. The anchor is lowered slowly by cable until it rests on the base end 10B of the body. In that position the fluke 6B is unbalanced. As the cable tied to eye 9 is released, the anchor will tend to fall over in the direction of arms 6B and the anchor will then rest on the flukes 6B and 6A or 6B and 6C. By this means the slot 16 will be in an upper position rather than be hidden under the anchor when it digs in. By pulling along the support end 10A, the flukes will

dig in, and the anchor will provide the desired restraint.

On the assumption that the anchor might dig in under a rock shelf, for example, so that it will be impossible to release the anchor by pulling in the direction of the end 10A, the anchor cable can be pulled in the opposite direction. The support member 12 is thus moved to the base end 10B. Then by pulling in the direction opposite to which the anchor was pulled when it was set, the anchor can be retrieved easily from any position where it might have been caught under an immovable object. 10

In FIGS. 3 and 6 is shown an additional weight 30, in the form of a spade, which can be attached as by bolts 32 to the arm 6B. As the anchor is lowered to the bottom it will, with more assurance, be tilted in the direction so as to dig in the fluke 6B with a companion 6A or 6C. 15

In FIG. 5 is indicated schematically an arrangement in which there are four flukes spaced at 60° angle from each other. Weights such as 30 of FIG. 6 can be applied to the flukes 6B and 6C so that the anchor will fall in such a direction that the two flukes 6B and 6C will dig in. The slot in the body will be uppermost, thereby permitting free movement of the support member 12 from one end of the body to the other. 20

While the invention has been described with a certain degree of particularity, it is manifest that many changes may be made in the details of construction and the arrangement of components. It is understood that the invention is not to be limited to the specific embodiments set forth herein by way of exemplifying the invention, but the invention is to be limited only by the scope of 25

the attached claim or claims, including the full range of equivalency to which each element or step thereof is entitled.

What is claimed:

1. A reversible anchor comprising:
a. a long cylindrical tubular body closed at both ends, and having a longitudinal slot the full length of the body and one-half of each end;
- b. a support member comprising a cylindrical neck portion, an eye on one end for attachment of the anchor cable, a spherical ball on the other end of said neck portion of size such as to slide freely inside the tubular body, said ball locked in by the two ends of said body but free to move from one end to the other of said body; and
- c. a plurality of arms or flukes attached to said body at a position near the base end of said body, said flukes spaced circumferentially on the side opposite said slot.
2. The anchor as in claim 1 including means to hinge said flukes so that they can rotate between an outer locked position and an inner folded position, substantially parallel to said body.
3. The anchor as in claim 1 including means to weigh at least one fluke on the side opposite said slot.
4. The anchor as in claim 1 including three flukes arranged 90° from each other with the center fluke 180° from said slot.
5. The anchor as in claim 1 including four flukes arranged 60° from each other on the side opposite to said slot.
